THREAD CLEANING AND TRUING DEVICE

Arthur P. Heldenbrand, Oklahoma City, Okla.

Application March 27, 1946, Serial No. 657,563

1 Claim. (Cl. 10—1)

1

My invention relates to an improvement in thread cleaning and trueing devices. While this device is designed for cleaning and trueing threads on oil well tubing and in couplings used therewith, the device is also applicable for use wherever threads are to be cleaned and trued up for reuse.

The object of the invention is to provide a simple, inexpensive and effective tool that may be run over threads that are corroded, full of dirt and the like, or threads that have become damaged from lying around, whereby they have been struck and damaged by some foreign article, or they may have been damaged in the operation of removing them from a well, or they may have become damaged from some other source or cause, but in running this tool over the threads, the threads will be cleaned and trued up ready for reuse.

A further object is to provide a tool of the kind mentioned that is light and easy to handle and can be operated successfully by hand.

Now referring to the accompanying drawings:

Fig. 1 is a side elevational view of the tool designed for working on the threads on the exterior of a piece of tubing or other material.

Fig. 2 is a top plan view of the tool shown in Fig. 1.

Fig. 3 is a bottom plan view of the tool shown in Fig. 1.

Fig. 4 is a detail vertical sectional view through the tool, the view being taken along the line IV—IV in Fig. 2, and looking in the direction of the arrows.

Fig. 5 is a cross sectional view of the device, the view being as seen from the line V—V in Fig. 1 and looking in the direction of the arrows.

Fig. 6 is a side view of the tool and a piece of threaded tubing, and illustrating how tool is used.

Fig. 7 is a side view of a modified form of the tool, the tool being adapted for use on internal threads as is in a pipe or tubing coupling.

Fig. 8 is a side view of the tool and a pipe or tubing coupling showing how the tool is used thereon, part of the coupling being broken away for convenience of illustration.

Similar numerals of reference designate the same parts throughout the several figures of the drawings.

In the drawings the tool is shown as being made of a piece of tubular spring material 10 and having internal threads 11. The tubular member 10 is cut from end to end leaving an open space or gap 12 from end to end of the tubular member 10. At other spaced locations around the

5 tubular member 10 are a plurality of cuts or slots 13 that extend from the bottom of the tubular member 10 to a point just a little above the threads 11 but terminating at a point well below the upper end of the tubular member 10.

Positioned within the upper end of the tubular member 10 is a spider element having preferably three legs 14, 15, and 16, each having a pin 14a, 15a, and 16a, the pin 15a somewhat loosely fitted in a hole 18, with the pins 16a and 14a slidably fitting in elongated holes or slots 19 and 17 so that the spider legs 16 and 14 can move slightly in the direction the tool is being rotated as the tool is used.

15 At the juncture of the legs of the spider and positioned on the center axis of the tubular member 10 is a standard or shaft 20, the lower end of which is rigidly connected, preferably by being welded, to the spider legs 14, 15, and 16 and projects upwardly therefrom. The upper or outer end of the shaft 20 is made multi-sided as at 20a as a wrench hold on which a wrench 21 may be placed and by which the tool may be turned to do the job of cleaning and trueing up of the threads being worked on.

20 The shaft 20 may also be provided with a hole 22 through the upper or outer portion thereof through which a bar or rod, not shown, could be passed and by which the tool could be turned instead of using the wrench 21.

The tool, as shown in Figures 1 to 6 inclusive operates as follows: As shown in Fig. 6, the tool is being used to clean and true up the threads 23 on the outside and end of the pipe or tubing 24. The tool body 10 being of a C spring tension type for the purpose of proper engagement of pipe threads is designed so that in a relaxed position neither pin 14a nor 16a is engaged with either end of the holes 17 or 19 but both pins are nearer the outside ends of the holes 17 and 19. To insure a free following of the threads in the tool between the threads on the pipe, and to maintain the proper thread engagements without excessive binding, the tool at no place must be allowed to forcibly contract so as to bind on the threads of the pipe. Therefore since the shaft 20 is rigid on the spider 14—15—16, and the spider pin 15a is stationarily mounted in the tool wall 10 and opposite the expansion and contraction gap 12, and by turning the tool by the shaft 20 in the direction of the arrow A, which is screwing the tool on the threads of the pipe, the spider pin 16a will engage the tool wall 10 at the end of the pin receiving opening 19 in the wall portions 30 B adjacent the gap 12 and will push the tool wall

10 to open or urge the further opening of the gap 12 whereby the circumference of the tool may be slightly and springably increased because of the heavy drag on the tool by the damaged pipe threads that are being reconditioned by the tool.

When turning the tool in the direction opposite to A, which is unscrewing, the pin 14a engages the end of the hole 17 and in a like manner, as in above paragraph, tends to open the gap 12 thus allowing a free turning movement of the tool.

In Figures 7 and 8 is shown substantially the same device as above described except that the device is designed for use on internal threads instead of external threads. In this design the threads 11a are on the outside of the tubular member 10a, and the reverse ends of the elongated slots 17 in the wall portion C and 19 in the opposing wall portion just across the gap 12 are set close to the pins 16a and 14a from that shown in Figures 1 and 6 inclusive, otherwise the design of the tool is the same as described. In the design in Figures 7 and 8, as the tubular member 10a is screwed into a female thread, for the purpose of straightening or making true those threads, the shaft 20 being attached stationary the same as in Figure 1. The pins 16a and 14a in a related position are not engaging either end of the holes 17 or 19 but are closer to the inside ends of both, that is the end nearer gap 12.

As herein before described the tool should engage the threads firmly but without binding while in a turning motion; therefore when a torque is applied to the shaft 20 in either direction the gap 12 must tend to close, making the circumference of the tool smaller, thereby causing a free following motion.

When turning tool in the direction of the arrow D, the pin 14a engages the end of hole 19 and when turning in the opposite direction the pin 16a engages the end of hole 17.

The cleaning, straightening and truing of the threads is dependent upon the clamping tension due to the quality and the rigidity of the spring design of the body 10a.

Such modifications of my invention may be employed as lie within the scope of the appended claim without departing from the spirit and intention of the invention. Now having fully shown and described my invention, what I claim is:

In a thread cleaning and truing device of the kind described; said device having a tubular portion, said tubular portion having a plurality of slots therethrough that extend from one end of the tubular element to points spaced away from

the other end of the tubular element, said tubular element having one slot therethrough that extends through the entire length of the tubular element, said slots defining leg portions of the major portion of the tubular element, said leg portions having threads thereon, and means for rotatably driving said tubular element from a point diametrically opposed to the slot extending the entire length of the tubular element and from a second point in advance of the slot extending through the entire length of the tubular element relative to the direction of rotation of the tubular element to permit and assist in the springable adjustment of the diameter of the tubular element during the process of cleaning and truing threads of the tubular goods, said means for rotatably driving the tubular element being a multi-legged spider element, one of the legs of the spider being stationarily engaged with the tubular element at the said point diametrically opposed to the said slot extending the entire length of the tubular element, a second leg of the spider element having its end portion movably seated in an elongated slot that is circumferentially disposed in the unthreaded portion of the tubular element and adjacent the slot extending the full length of the tubular element, the last said leg end being engageable with the tubular element wall at either end of the said elongated slot, a third spider leg, the end portion of the third spider leg being movably seated in a second elongated slot that is in circumferential alignment with the first said elongated slot, the third said spider leg end being unengageable with the wall of the tubular element at either end of its respective elongated slot by the limitation of the movement of the second spider leg end in its respective elongated slot whereby the tubular element may be rotarily driven by the spider and still left free for expansive movements as afore mentioned, and shaft means on said spider for turning the spider and associated parts.
